UNITED STATES PATENT OFFICE.

CHARLES J. MUEND, OF PHILADELPHIA, PENNSYLVANIA, ASSIGNOR TO HAINES,
JONES & CADBURY INCORPORATED, A CORPORATION OF PENNSYLVANIA.

DESIGN FOR A FAUCET.

Application filed December 28, 1921. Serial No. 525,486. Term of patent 14 years.

To all whom it may concern:

Be it known that I, CHARLES J. MUEND, a citizen of the United States, residing at Philadelphia, in the county of Philadelphia, State of Pennsylvania, have invented a new, original, and ornamental Design for Faucet, of which the following is a specification, reference being had to the accompanying drawings, forming part thereof.

The figures are respectively a view in perspective and a view in plan of a faucet showing my new design.

I claim:—

The ornamental design for a faucet, as shown.

CHARLES J. MUEND.
